(57) **CLAIM**

The ornamental design for a disposable dishware, as shown and described.

DESCRIPTION

FIG. 1 is a front right-top perspective view of a disposable dishware, showing my new design;

FIG. 2 is a front elevation view thereof, the rear elevation view thereof being a mirror image;

FIG. 3 is a left elevation view thereof, the opposite being a mirror image;

FIG. 4 is a top plan view thereof;

FIG. 5 is a bottom plan view thereof; and,

FIG. 6 is a front right-bottom perspective view thereof.
